United States Patent

Des. 239,441

Patented Apr. 6, 1976

239,441

TIRE

Mitsuhisa Yahagi, Tokyo, and Shigeo Makino, Tokorozawa, Japan, assignors to The Furukawa Electric Company Limited, Tokyo, Japan

Filed Sept. 13, 1974, Ser. No. 505,564

Claims priority, application Japan Mar. 29, 1974

Term of patent 14 years

Int. Cl. D12—15

U.S. Cl. D12—142

FIG. 1

FIG. 2

FIG. 3

FIG. 4

FIG. 1 is a front elevational view of a tire showing our new design, it being understood that the tread pattern is repeated throughout the circumference of the tire;

FIG. 2 is a side elevational view thereof, the opposite side being a mirror image of the side shown herein;

FIG. 3 is a perspective view thereof; and

FIG. 4 is an enlarged fragmentary cross-sectional view thereof taken along the line 4—4 in FIG. 1.

We claim:

The ornamental design for a tire, substantially as shown and described.
